Charles V. Wilson

United States Patent Office.

CHARLES V. WILSON, OF NEWARK, NEW JERSEY.

Letters Patent No. 65,850, dated June 18, 1867.

IMPROVEMENT IN POTS FOR LEAD BATH FOR TEMPERING STEEL, &c.

The Schedule referred to in these Letters Patent and making part of the same.

TO ALL WHOM IT MAY CONCERN:

Be it known that I, CHARLES V. WILSON, of the city of Newark, in the county of Essex, and State of New Jersey, have made an improvement on Making a Pot or Bath for the Heating of Steel for Forging or Tempering; and I do hereby declare the following to be a full and exact description of the same, reference being herein had to the drawings that accompany this specification, and which make part of the same—

Figure 1 being a section, and

Figure 2 a perspective view of the bath.

The nature of my improvement consists in combining a wrought-iron interior with a cast-iron exterior in the construction of the pot or bath.

It has been found in practice that constant use of a cast-iron pot to hold the lead tends to such a porosity in the iron as to materially waste the lead, the more especially as it is very rare for cast iron to be free from air-holes. To obviate this I form a wrought-iron receiver for the lead, of any desired thickness and size, as shown at *b* in the drawings, and have a cast-iron case, *a*, of the necessary form and thickness, combined therewith at the foundry, thus forming a pot or bath that is more economical of the lead, and will last longer than the casting alone.

What I claim as my improvement, and desire to secure by Letters Patent, is—

The pot or bath made of wrought and cast iron, combined substantially in the manner and for the purpose hereinabove specified.

Witnesses:

W. M. GOODING,

ALBERT J. DAVIS,

CHARLES V. WILSON.
